UNITED STATES PATENT OFFICE.

ROBERT W. SCOTT, OF LEEDS POINT, NEW JERSEY, ASSIGNOR, BY DIRECT AND MESNE ASSIGNMENTS, TO SCOTT & WILLIAMS, INCORPORATED, OF CAMDEN, NEW JERSEY, A CORPORATION OF NEW JERSEY.

NEEDLE FOR KNITTING-MACHINES.

1,062,366.

Specification of Letters Patent. Patented May 20, 1913.

Application filed June 4, 1908. Serial No. 436,706.

To all whom it may concern:

Be it known that I, ROBERT W. SCOTT, a citizen of the United States, residing in Leeds Point, Atlantic county, New Jersey, have invented certain Improvements in Needles for Knitting-Machines, of which the following is a specification.

My invention consists of an improvement in knitting machine needles of the type shown in my Letters Patent No. 884,763, dated October 30, 1906, the object of my present invention being to so construct such a needle that it will spread the stitch which is being transferred from it to another needle, and will thus facilitate the application of said stitch to the receiving needle. This object I attain in the manner herein-after set forth, reference being had to the accompanying drawing, in which—

Figure 1 is a perspective view, on enlarged scale, of one type of knitting machine needle embodying my invention; Fig. 2 is a section of the same on the line *a—a*, Fig. 1; Fig. 3 is a perspective view of another type of needle embodying my invention, and Fig. 4 is a perspective view illustrating a modification of the invention.

The needle shown in Figs. 1 and 2 has a stem 1 with hooked end 2 and swinging latch 3, said stem projecting from a shank 4 which is disposed at an angle in respect to the stem. The bend between the stem and the shank of the needle has a grooved face 5 and is expanded laterally in respect to the stem and shank as shown at 6 in Figs. 1 and 2, whereby, when the needle is projected to make a transfer and the stitch to be transferred is hanging on the bend of the needle, said stitch will be spread laterally and its application to the receiving needle will be correspondingly facilitated.

In Fig. 3 I have illustrated the application of my invention to another type of needle, shown in my Letters Patent before referred to, said needle having a straight stem 7, with projecting loop 9 thereon, the bend between the upper member of this loop and the upper portion of the stem of the needle being laterally expanded and grooved in the same manner as the bend at the junction of the two members of the needle shown in Fig. 1.

When that portion of the needle which constitutes the bend is grooved in advance of the bending operation, the latter operation will naturally cause the lateral expansion of the metal at the bend, but the grooving of this portion of the face of the needle, while preferable, is not essential in all cases, as that portion of the needle which is to constitute the bend may, if desired, be flattened and laterally expanded either before or after the bending operation, as shown for instance at 10 in Fig. 4.

I claim:

1. A knitting machine needle having a stem bent so as to present members at an angle to one another, the metal of which the bent portion of the stem is composed being expanded laterally.

2. A knitting machine needle having a stem bent so as to present members at an angle to one another, said stem having a grooved and rigid lateral expansion at the bend.

In testimony whereof, I have signed my name to this specification, in the presence of two subscribing witnesses.

ROBERT W. SCOTT.
